RADIO TUBE AND SOCKET STRUCTURE

Leslie J. Woods, Philadelphia, Pa., assignor, by
mesne assignments, to Pennsylvania Patents,
Inc., Carson City, Nev., a corporation of
Nevada

Application April 18, 1938, Serial No. 202,781

9 Claims. (Cl. 250—27.5)

This invention relates to radio tube sockets and, more particularly, to a socket structure employing novel means for supporting a radio tube and for holding the socket parts together in assembled relation.

One object of the invention is to provide in a socket structure a novel device for holding or anchoring a radio tube in cooperative relation with the socket and for insuring proper positioning of the tube relative to the socket.

Another object of the invention is to provide a device of this character which firmly engages and is interlockable with a pin carried by the tube base, thus insuring firm mechanical support of the tube and also permitting the use of the pin and holding device as electrical elements.

A further object of the invention is to provide a novel holding device of the stated character which functions additionally to secure the parts of the socket structure together in proper assembled relation.

Still another object of the invention is to provide a socket in which certain contact elements are electrostatically shielded from other elements, thus minimizing the capacitive coupling between said contacts.

The invention may be fully understood from the following detailed description in connection with the accompanying drawing, wherein

Fig. 1 is an elevational view of the socket with a tube in cooperative relation therewith;

Fig. 2 is a plan view of the socket;

Fig. 3 is a bottom view of the same;

Fig. 4 is an elevational view of the lower portion of the tube removed from the socket and illustrating more clearly the interlocking feature;

Fig. 5 is a sectional view taken along line 5—5 of Fig. 2;

Fig. 6 is a fragmentary sectional view taken along the line 6—6 of Fig. 2; and

Fig. 7 is a perspective view of the holding member or device provided by the invention.

Referring to the several views of the drawing, the socket structure comprises a socket base preferably formed by a pair of superposed insulating plates 1 and 2 which may be formed of any suitable insulating material, for example, resin-impregnated fibrous material. These plates serve to support the contact elements 3, the plate 1 serving as a base or mounting plate, while the plate 2 serves as a cover or clamping plate. While any suitable form of electrical contact element may be employed, the contact elements 3 preferably take the form of those disclosed and claimed in the copending application

of Loy E. Barton, Serial No. 202,782, filed April 18, 1938. It will be noted particularly from Fig. 6 that each of these contact elements comprises a bent metallic strip extending loosely through an opening 4 in the plate 1 and extending radially inward between the plates, and terminating in a prong-receiving portion 5 disposed transversely of the aligned openings 6 and 7, which are provided in the respective plates 1 and 2 for the reception of a tube prong. The tube base 8 carries prongs 9 for engagement with the contact elements 3.

In accordance with the present invention, there is provided centrally of the socket structure a holding member or device 10, and there is also provided centrally of the tube base an extending pin 11 for cooperative engagement with the device 10. The pin 11 is of substantial diameter and length, as shown in Fig. 4, and at its lower end, it is provided with a circumferential recess 12, the purpose of which will appear presently. While the pin 11 may be formed of any suitable material, it is preferably formed of metal to permit its use as an additional terminal or connector member, as mentioned further hereinafter.

The device 10 is preferably formed from a single piece of resilient sheet metal by stamping a suitable blank from the metallic sheet and then bending or pressing the blank to the shape and form illustrated in Fig. 7. The complete device 30 comprises a cylindrical portion 13 having a crimp flange 15 spaced from the end thereof, and having depending resilient fingers 16. There is also provided longitudinally of the device a pressed-out portion 17 forming an internal longitudinal recess 18, the purpose of which will be apparent presently. Preferably, the pressed-out portion 17 is located diametrically opposite the longitudinal slit 19 resulting from the bending of the metal piece to the cylindrical form. There is also preferably provided a terminal lug extension 20 at the lower end of the pressed-out portion 17.

As shown in Figs. 5 and 6, the cylindrical portion 13 extends through aligned central openings in the plates 1 and 2 with the crimp flange 15 engaging the lower face of plate 1, while an end flange 14 engages the upper face of plate 2. Between the plates and surrounding the cylindrical portion 13, there is provided a spacing washer 21 which separates the plates sufficiently to accommodate the contact elements 3 and permit movement thereof parallel to the plates. The end flange 14 is turned over after the several parts are assembled. Thus, the upper portion of the holding device 10 secures the parts of the

socket structure in assembled relation and takes the place of the rivet or rivets which have been used for this purpose in the past. The central apertures in the plates 1 and 2 through which the device 10 extends are provided with recesses to accommodate the pressed-out portion 17, thus locking the device against rotation.

The recess 18 serves as a keyway for the longitudinal rib or key 22 provided on the pin 11, 10 thus insuring proper positioning of the tube relative to the socket when the tube is inserted. Thus, the device 10 serves additionally as a positioning member for the tube. Consequently, the tube prongs and the prong-receiving holes and 15 contact elements of the socket may be equally spaced, as shown in Figs. 2 and 3.

At their lower ends, the resilient fingers 16 are pressed inwardly, as at 23, thus forming collectively an annular detent means adapted to seat 20 in the recess 12 of pin 11, as indicated in Fig. 4. That is to say, when the tube is fully inserted in the socket, the inwardly-bent end portions of the fingers 16 are seated in the recess 12 and thus interlock the pin 11 and the holding device 10. 25 Additionally, there is provided an annular spring 24 in the form of a split resilient ring which is seated in the annular recess formed by the bending inward of the fingers 16. This spring resiliently resists outward movement of the fingers 30 16 and maintains the detent portions of the fingers in the recess or groove 12. There is thus provided a very strong mechanical interlocking of the tube with the socket structure which maintains the tube in proper relation with the socket.

35 It is, of course, now common practice to ship radio sets complete with tubes, and similar conditions obtain in automobile radio receivers. To avoid the necessity of maintaining the sets so that the tubes are in upright position in transitu 40 and hence will not fall out, it is desirable that the tubes be firmly held in their sockets. The interlock of the present invention requires a very strong direct pull to disengage the tube from its socket, and tests have shown that extreme jerks 45 will not remove the tube even when it is weighted. Hence the tube may be safely shipped in its socket without danger of its falling out. On the other hand, it is necessary, on occasion, to remove tubes 50 for replacement and test purposes. In accordance with the present invention the tube may be removed from its socket by levering it out. To this end the tube base 8 is provided with an annular rim 25 which may be used as a pivot or fulcrum. Hence to remove the tube from the socket 55 the top of the tube is pushed transversely of the socket thus rocking the tube about the fulcrum 25. As the leverage thus effected is of the order of six to one, the tube member 12 is thus withdrawn from the grip of the fingers 16 and after 60 that the tube can easily be lifted out. To assist in locating the tube in the socket by indexing the key 22 with the channel 18, a small dimple 26 may be radially aligned with key 22 on the outer rim of the tube base 8.

65 The base member 8 of the tube is preferably of metal and in combination with the holding member 10 forms an electrostatic shield between the various contact pins. It is highly desirable that the capacity between various elements of the tube, for example the grid and plate, and the 70 electrical connections to these elements, be minimized as far as possible. By grounding the holding member 10 and using diametrically opposite contacts for the critical elements, the capacity between these elements may be minimized to such

an extent that both the grid and plate leads of the tube of such critical devices as radio frequency amplifiers may be brought out at the bottom of the tube without employing neutralizing circuits. The shielding thus afforded by the 5 holding member 10 may be augmented by grounding some of the other contacts for radio frequency currents. Additionally the contact pins 9 should preferably be as short as possible. Electrical connections to the holding member 10 may 10 be made by means of the terminal lug 20.

The holding device provided by this invention, as above described, permits the use of smaller prongs on the tube, since the prongs are not required to function as mechanical supports, and 15 also permits the use of prong-receiving elements on the socket which are required only to make good electrical contact with the prongs. The tube prongs may be smaller in diameter and shorter in length than those used heretofore and, 20 by reason of the short length of the prongs, they may be protected against injury by the pin 11 and the tube base. This may be seen from Fig. 4, in which it will be noted that the prongs 9 are of such short length that they are within the protected area defined by the cone formed by the end 25 of the member 11 and the tube base 8. Hence there is little chance of them striking any surface.

Thus it will be seen that the invention provides a novel multi-function holding device in a radio 30 tube socket having the several advantages above set forth. While a single preferred embodiment of the invention has been illustrated and described, it will be obvious that various modifications, particularly in the details of the structure, 35 may be resorted to without departing from the invention.

I claim:

1. A radio tube and socket structure, comprising a tube base having contact prongs extending 40 therefrom, a mounting and aligning pin extending from said base and having a circumferential recess and a longitudinal key, a socket base, contact elements carried by said socket base for electrical engagement with said prongs, and a holding and supporting member carried by said socket 45 base and having annularly arranged resilient fingers for receiving and supporting said pin, one of said fingers being recessed longitudinally to provide a keyway for said key, the other fingers 50 resiliently gripping said pin and having inwardly bent portions forming annular detent means to interlockingly engage said circumferential recess.

2. A radio tube and socket structure, comprising a tube base having contact prongs extending therefrom, a mounting and aligning pin extending from said base, a socket base, contact elements carried by said socket base for electrical engagement with said prongs, means for supporting said tube in said socket and for preventing direct withdrawal therefrom, comprising a resilient holding member carried by said socket base for receiving said pin, said member having a flange extending above said base, annular detent 65 means on said pin and said member for interlockingly engaging said pin with said member, and preventing direct withdrawal of the pin, and means for unlocking said detent means by transverse movement of the top of the tube comprising 70 a peripheral rim on the base of said tube for forming a fulcrum on which the tube may be rocked to unlock the detent means.

3. In a radio tube and socket structure, a tube base having a substantial rigid support pin and 75

5 relatively non-rigid contact prongs projecting therefrom, and a socket cooperating with said base, said socket comprising superposed thin plates having apertures for said pin and said prongs and carrying a hollow tube-like supporting member fixedly positioned in the aperture for said pin, and resilient contacts loosely held by said plates in alignment with the apertures for said prongs, said member having a tubular portion adapted to snugly engage said pin and a portion comprising annularly arranged longitudinal fingers adapted to resiliently engage said pin, whereby said pin and said member substantially entirely support said tube in said socket.

10 4. In a radio tube and socket structure, a tube base, contact prongs of small diameter and length carried by said base, a socket base, contact elements on said socket base for receiving said prongs, the prongs and associated contact elements making good electrical contact but being incapable of furnishing mechanical support for the tube, and means for supporting and securing the tube on the socket base and preventing lateral movement of the tube, said means comprising a cylindrical center pin on said tube base of relatively large diameter and of relatively great length, and a hollow cylindrical member on said socket base constructed and arranged to snugly engage said pin over substantially its entire cylindrical surface throughout substantially the entire length of the pin.

15 5. In a radio tube and socket structure, the combination with a tube base and a socket base carrying contact elements adapted to make good electrical contact but incapable of mechanically supporting the tube on the socket base, of means for supporting and securing the tube on the socket base and preventing lateral movement of the tube, said means comprising a cylindrical center pin on said tube base of relatively large diameter and of relatively great length, a hollow cylindrical member on said socket base constructed and arranged to snugly engage said pin over substantially its entire cylindrical surface throughout substantially the entire length of the pin, and cooperating interlockable detent portions at the lower ends of said pin and said member.

20 6. A radio tube and socket structure, comprising a tube base and contact prongs carried thereby, a multi-part socket base and prong-receiving contacts carried thereby, and means for securing the parts of the socket base together and for holding the tube firmly on the socket base, said means comprising a cylindrical center pin on said tube base of relatively large diameter and of relatively great length, a hollow cylindrical member on said socket base constructed and arranged to snugly engage said pin over substantially its entire cylindrical surface throughout

25 substantially the entire length of the pin, a flange at the upper end of said member and a crimp flange intermediate the ends of said member for engaging opposite faces of the multi-part socket base, a circumferential recess at the lower end of said pin, a plurality of depending resilient fingers on said member having their lower ends indented to interlockingly engage said recess, and a spring member surrounding the indented ends of said fingers.

30 7. A radio tube and socket structure, comprising a tube base having contact prongs extending therefrom, a mounting and aligning pin extending from said base and having an annular recess, a socket base, contact elements carried by said socket base for electrical engagement with said prongs, means for supporting said tube in said socket and for preventing direct withdrawal therefrom, comprising a resilient holding member carried by said socket base for receiving said pin, said member having a flange extending above said base and resilient indented fingers extending below said base with a spring member surrounding the indented fingers for interlocking engagement with the recess of said pin and preventing direct withdrawal of the pin, and means for unlocking the interlocked pin and holding member by transverse movement of the top of the tube comprising a peripheral rim on the base of said tube for forming a fulcrum on which the tube may be rocked to unlock the pin and holding member.

35 8. In a radio tube and socket structure, the combination with a tube base and a socket base carrying contact elements adapted to make good electrical contact but incapable of efficiently supporting the tube on the socket base, of means for efficiently supporting and securing the tube on the socket base, said means comprising a rigid pin on said tube base, a hollow pin-receiving member on said socket base having resilient fingers arranged to grip said pin, and cooperating interlockable detent portions on said pin and said member to secure the tube firmly on the socket base.

40 9. In a radio tube and socket structure, the combination with a tube base and a socket base carrying contact elements adapted to make good electrical contact but incapable of efficiently supporting the tube on the socket base, of means for efficiently supporting and securing the tube on the socket base, said means comprising a rigid pin on said tube base, a hollow pin-receiving member on said socket base having a resilient portion extending below the socket base and adapted to grip said pin, and cooperating interlockable detent portions on said pin and said member to secure the tube firmly on the socket base.
